PHOTOELECTRIC MUSICAL TONE GENERATOR

Bruce C. Haack, 228 W. 72nd St., New York, N.Y.
10023, and Phyllis J. Horowitz, 3359 Ocean Ave.,
Oceanside, N.Y. 11572

Filed Dec. 19, 1969, Ser. No. 20,574

Term of patent 14 years

Int. Cl. D17—99

U.S. Cl. D56—1

FIG. 1 is a top plan view of a photoelectric musical tone generator embodying our new design;

FIG. 2 is a side elevational view thereof;

FIG. 3 is a front end view thereof; and

FIG. 4 is a rear end view thereof.

The small tubular portion is broken away in FIGS. 1 and 2 to indicate indeterminate length.

We claim:

The ornamental design for a photoelectric musical tone generator, substantially as shown and described.
